UNITED STATES PATENT OFFICE.

CHARLES E. BILLINGS, OF HARTFORD, CONNECTICUT.

DESIGN FOR A WRENCH.

SPECIFICATION forming part of Design No. 26,111, dated September 29, 1896.

Application filed August 13, 1896. Serial No. 802,672. Term of patent 14 years.

To all whom it may concern:

Be it known that I, CHARLES E. BILLINGS, a citizen of the United States, residing at Hartford, in the county of Hartford and State of Connecticut, have invented and produced a new and original Design for a Wrench, of which the following is a specification.

In the drawings accompanying and forming part of this specification, Figure 1 is a perspective view of the parts of the wrench when assembled for use, showing my design. Fig. 2 is a cross-section on line *a a*, Fig. 1. Fig. 3 is a rear end view of the assembled parts, and Fig. 4 is a perspective view of the sliding jaw of the wrench detached.

Similar characters designate like parts in all the figures of the drawings.

The leading features of my design consist in the representation of a fixed jaw of a wrench having flat sides, rounded edges, a flat forward end with an offset shoulder or working surface and a curved rear end, the said jaw being hollow and serving as a sheath to receive the sliding jaw, and in the representation of a sliding jaw having grooved or channeled sides with curved back and curved ends and a flat working edge in which the usual teeth to receive the threads of the actuating worm or screw are formed. The top of the fixed jaw or sheath is flat to afford the usual grasping-surface, and the sides of said flat portion are located in a plane below the end of the fixed jaw or sheath and merge with the latter by curved lines.

The numeral 1 represents the fixed hollow jaw or sheath of the wrench, having flat sides 2, curved edges 3, and a rounded or curved rear end 4.

The numeral 5 represents the flat working surface of the sheath or fixed jaw, which is joined to the latter by curved lines 5', and is also provided on its under side with a longitudinally and transversely curved surface 5''.

The numeral 6 represents the movable jaw of the wrench, having a groove or channel 7 7' on each side thereof and provided with a curved back 8 and a flat working edge 9, the form being substantially that of an I or girder beam. The rear end of the movable jaw is curved, as represented at 10, to conform to the curvature of the corresponding end 4 of the fixed jaw, and the upper end of said movable jaw is flattened or reduced at 11, said reduced portion having a curved periphery 12 and being united with the main body of the jaw by curved lines 13.

It is to be observed that the grooves or channels 7 7' merge into the flattened portion 11, and therefore enhance the effect and beauty of the design.

By virtue of the curved outlines of the design a pleasing effect is produced, and the device is also admirably adapted for use as a pocket implement, as, owing to its shape, it can be inserted in and withdrawn from a pocket without hindrance or obstruction.

Having described my invention, I claim—

The design for a wrench, substantially as shown and described.

CHARLES E. BILLINGS.
